UNITED STATES PATENT OFFICE.

CHARLES J. AHRENFELDT, OF NEW YORK, N. Y.

DESIGN FOR A COVERED DISH.

SPECIFICATION forming part of Design No. 29,123, dated August 2, 1898.

Application filed February 9, 1898. Serial No. 669,725. Term of patent 7 years.

To all whom it may concern:

Be it known that I, CHARLES J. AHRENFELDT, a citizen of the United States, residing at the city of New York, in the county and 5 State of New York, have invented and produced a new and original Design for a Covered Dish, of which the following is a specification.

My design consists of a covered dish having the shape and ornamentation hereinafter 10 shown and described, reference being had herein to the accompanying drawings, forming a part hereof, in which like letters of reference refer to like parts in each figure.

Figure 1 is a side view of a covered dish 15 embodying my design. Fig. 2 is a top view of the same. Fig. 3 is a vertical cross-section of the same, taken on the lines 3 3 of Fig. 2. Fig. 4 is a bottom view of the same.

The body of the dish A and cover A' are 20 multifoil in form, having a series of indentations B in the base of the dish and B² in the lid, leading to lines of depression B', extending up the sides of the dish and radially from the indentations B² in the periphery of the 25 cover or lid toward the center thereof and merging in the surface of the said cover at or near the said center. The body of the dish is provided with a circumferential ornamentation consisting of a band of latticed work C, 30 the lines of which are provided with small circles c at the points of intersection, bordered on either side by a series of parallel scrolls D with volute terminals d and fin-like projections d' on the inner side near the said

terminals, and directly above each upper bordering scroll a cruciate leaf ornament E with two foliate ornaments e on either side and a scroll E' having volute terminals. The handles of the dish F are provided with latticed-work ornamentation F' around their outer 35 sides similar to the ornamentation on the body of the dish, bordered by scrolls F² with volute terminals. The cover of the dish is provided, between the periphery and the center thereof and extending around the said 40 center and parallel to the said periphery, with an ornamentation II in all respects similar to the circumferential ornamentation upon the body of the dish. Within this ornamentation and at the points where the handles of the cover are joined to the same small 45 tendril-like scrolls G are located, two proceeding from each terminal of the handle and extending outwardly toward the band of ornamentation II. The handle I of the cover 50 is quatrefoil in form, being bordered on either side by scroll-like ornamentations I' with volute terminals.

What I claim is—

The design for a covered dish herein shown 60 and described.

In witness whereof I have hereunto affixed my signature in the presence of two witnesses.

CHARLES J. AHRENFELDT.
